UNITED STATES PATENT OFFICE.

FRANK M. CHAPMAN, OF FORT EDWARD, NEW YORK, ASSIGNOR OF
THREE-FOURTHS TO WILLIAM J. GALLAGHER, OF SANDYHILL,
NEW YORK.

PULP-SCREEN.

No. 806,641.

Specification of Letters Patent.

Patented Dec. 5, 1905.

Application filed April 8, 1905. Serial No. 253,519.

To all whom it may concern:

Be it known that I, FRANK M. CHAPMAN, a citizen of the United States, residing at Fort Edward, in the county of Washington and State of New York, have invented certain new and useful Improvements in Pulp-Screens; and I do hereby declare the following to be a full, clear, and exact description of the invention, such as will enable others skilled in the art to which it appertains to make and use the same.

My invention relates to machines for screening pulp in the manufacture of paper, and particularly to that class of screens in which flat screen-plates are used.

The objects of this invention are to produce a better product in much less time than it takes with a screen-plate of the same size in screens heretofore known and used.

Flexible diaphragms have been used below the screen-plates and piston and cam mechanism provided for reciprocating the diaphragm to draw the material, which is introduced upon the upper surface of the screen-plates, through said plates.

My present invention consists in mounting a second diaphragm above the screen-plate and providing means to reciprocate it with the diaphragm below the screen-plate. I have found that by using two diaphragms arranged in this manner just about three times as much stock can be run through the same size plate as can be done by any screen heretofore known to me. My screen can also clean more stock through a plate of a finer mesh, as the upward movement of the upper diaphragm by suction tends to raise any pieces of coarse pulp which may be covering perforations in said plate and preventing the passage of the finer pulp therethrough.

The invention also consists in certain novel means of cleaning the screen-plate and removing the refuse from the screen and in the other features of construction and combinations of parts hereinafter described, and more particularly pointed out in the claims concluding this specification.

In the accompanying drawings, illustrating the preferred embodiment of my invention, Figure 1 is a side view of a machine made in accordance with my invention with a portion of the upper part thereof in vertical section. Fig. 2 is a broken end view with the upper part in vertical section.

While the preferred embodiment of my invention is illustrated in the accompanying drawings and its construction and operation are described in this specification, the right is reserved to make such changes from the construction shown and described herein as the scope of the claims hereto appended will permit.

In carrying out the invention the screen-plate is arranged in a suitable casing, preferably in a horizontal position. The diaphragms are preferably mounted parallel to the screen-plate, one set above and another below said plate in the casing. Pistons secured to said diaphragms are actuated to reciprocate the latter by pitmen carrying cam-shoes adapted to work on cams on a shaft mounted near the base of the frame, the piston on the upper and lower diaphragms being connected together in pairs by rods extending through the screen-plate. Downwardly-extending sleeves are preferably secured to the under surface of said plate at the openings for the passage of the connecting-rods, whereby said rods and pitmen are steadied and retained in vertical positions as they move up and down. The parts are further retained in vertical positions and their downward stroke assured by the guards at the bottom of the pitmen fitting around vertical pins and below coiled springs arranged on said pins. The material to be screened is fed to the screen-plates from an inlet-box or trough, preferably running the entire length of the screen. The stock which goes through the plates passes out into the flow-box arranged below the inlet-box, which also preferably extends the whole length of the screen. On the opposite side of the screen-casing is a longitudinal opening or series of openings normally closed by spring-pressed plates arranged on the outside. Rods provided with handles on their outer ends extend through said closure-plates and carry scraper-plates on their inner ends.

The normal position of said scraper-plates when their operating-rods are thrust in is near the inlet side of the screen. A vertically-arranged strip is placed longitudinally of the screen just within the inlet-opening and extends slightly above said opening, acting as a trap and as a protection for the scraper-plates which normally lie beside it. When it is desired to clean the screen-plates, the scraper-plates are drawn

across said plates by means of their operating-rods, and when they reach a point near the other side of the screen the closure-plates are engaged and pressed outward by lugs or 5 projections on the rods, so that the completion of the stroke of said rods and scrapers removes the refuse from the screen through the openings in the casing. On the opposite stroke the springs mounted behind the closure- 10 plates cause said plates to close the openings. By limiting the strokes of the scraper so that the lugs or the rods will not come in contact with and open the closure- plates said scraper may be used simply as a 15 scraper to facilitate the passage of the stock through the screen.

Referring more particularly to the drawings, 1 is the body or casing of the screen supported on legs 2, in which are journaled the 20 shaft 3, carrying the drive-pulley 4 and a series of cams 5, upon which the cam-shoes 6 of the pitmen 7 rest and by means of which said pitmen are operated. Each of the pitmen is provided with a projecting guard 8, fitting around a pin 9, mounted vertically on the journal-boxes for the shaft and having a coiled spring 10 around it engaging said guard and normally holding the cam-shoe down upon the cam. Said pitmen support 25 30 on their upper ends the pistons 11, secured to the lower diaphragms 12, and rods 13 extend through the screen-plates 14 and connect said pistons with the pistons 15, secured to the upper diaphragm 16. The downwardly- 35 extending tubular sleeves in which the rods 13 work are designated 17. The inlet-box or trough 18 and the outlet or flow-box 19 are shown at the left of Fig. 2, as is also the vertical strip 20, extending above the inlet- 40 openings just within the casing. The coiled springs 21 for retaining the closure-plates 22 in place are arranged within brackets 23, through which extend the handles 24 of the operating-rods 25 for the scrapers 26. Each 45 of said scrapers, as shown, has a square block 27 secured upon its operating-rod ahead of the scraper-plates proper by means of a nut 28, which is adapted to come in contact with and press outward the closure- 50 plate opposite it when the scraper is drawn across a full stroke, as where it is desired to remove the refuse. It is obvious that any other form of projection or lug on the rods 25 would serve the purpose of the block 55 and nut 28 and may be used in place thereof without departing from the spirit of my invention. It should also be understood that by providing the upper diaphragm of the same size as and adapted to be reciprocated with the 60 lower diaphragm the output of my machine will be three times that of one wherein only the lower diaphragm is used. This has been found by practical experience to be true, and, more than that, my machine turns out a 65 better product than a single-diaphragm

machine and is capable of screening pulp through screen-plates of a finer mesh.

Having thus described my invention, what I claim as new, and desire to secure by Letters Patent, is—

- 70 1. In a machine of the character described, the combination with a screen-plate, of a diaphragm arranged above said plate, and means to reciprocate said diaphragm.
- 75 2. In a machine of the character described, the combination with a screen-plate, of a diaphragm arranged above and parallel to said screen-plate, and means to reciprocate said diaphragm.
- 80 3. In a machine of the character described, the combination with a screen-plate, of a series of diaphragms arranged above said plate, and means to reciprocate said diaphragm.
- 85 4. In a machine of the character described, the combination with a screen-plate, of a diaphragm arranged below said plate, a second diaphragm arranged above said plate, and means to reciprocate said diaphragms.
- 90 5. In a machine of the character described, the combination with a screen-plate, of a diaphragm arranged below said plate, a second diaphragm arranged above said plate, and means to reciprocate said diaphragms together.
- 95 6. In a machine of the character described, the combination with a screen-plate, of a series of diaphragms arranged below said plate, a second series of diaphragms arranged above said plate, means to reciprocate said diaphragms.
- 100 7. In a machine of the character described, the combination with a screen-plate, of a series of diaphragms arranged below said plate, a second series of diaphragms arranged above said plate, and means to reciprocate said diaphragms together in pairs.
- 105 8. In a machine of the character described, the combination with a screen-plate, of a diaphragm arranged below and parallel to said plate, a second diaphragm arranged above and also parallel with said plate, and means to reciprocate said diaphragms.
- 110 9. In a machine of the character described, the combination with a screen-plate, of a diaphragm arranged below and parallel to said plate, a second diaphragm arranged above and also parallel to said plate, and means to reciprocate said diaphragms simultaneously.
- 115 10. In a machine of the character described, the combination with a screen-plate, of a diaphragm arranged above said plate, a pitman adapted to reciprocate said diaphragm and extending through said plate, and means to reciprocate said pitman.
- 120 11. In a machine of the character described, the combination with a screen-plate, of a diaphragm arranged above said plate, a pitman adapted to reciprocate said diaphragm, extending through said plate, a sleeve on said plate, fitting around said pit- 125
- 130

man and adapted to guide the same, and means to reciprocate said pitman.

12. In a machine of the character described, the combination with a screen-plate, of a diaphragm arranged above said plate, a pitman adapted to reciprocate said diaphragm and extending through said plate, a laterally-extending guard, on said pitman, mounted around a pin secured to a fixture, a coiled spring on said pin adapted to press down on said guard, and cam mechanism to reciprocate said pitman.

13. In a machine of the character described, the combination with a screen-plate, of a diaphragm arranged below said plate, a pitman adapted to reciprocate said diaphragm, a laterally - extending guard, arranged on said pitman, mounted around a pin secured to a fixture, a coiled spring on said pin, adapted to press down on said guard, and cam mechanism to reciprocate said pitman.

14. In a machine of the character described, the combination with a screen-plate, of a diaphragm arranged below said plate, a second diaphragm arranged above said plate, a pitman secured to one of said diaphragms and having an arm extending through said screen-plate and connecting said diaphragm, and means to reciprocate said pitman.

15. In a machine of the character described, the combination with a diaphragm arranged below said plate, a second diaphragm arranged above said plate, a pitman secured to one of said diaphragms and having an arm extending through said plate and connecting said diaphragms together, a sleeve on said screen-plate fitting around said arm and acting as a guide for the same, and means to reciprocate said pitman.

16. In a machine of the character described, the combination with a casing having an opening on its side, of a screen-plate arranged in said casing on a level with said opening, a spring - pressed closure for said opening, a scraper, and a rod, for operating said scraper, extending through said closure

and having a lug or projection, arranged near the scraper, adapted to engage with said closure to remove the same from the opening to permit of the removal of the refuse from the screen.

17. In a machine of the character described, the combination with a casing having an opening in its side, of a screen-plate arranged in said casing on a level with said opening, a bracket secured to said casing, a spring arranged between said bracket and said closure whereby the latter is pressed over said opening, a scraper, and a rod, for operating said scraper, extending through said closure and having a lug or projection, arranged near the scraper, adapted to engage said closure to remove the same from the opening to permit of the removal of the refuse from the screen.

18. In a machine of the character described, the combination with a casing having an opening in its side, of a screen-plate arranged in said casing on a level with said opening, a bracket on said casing, a closure for said opening, a scraper, a rod, for operating said scraper, extending through said closure and bracket, a coiled spring arranged around said rod between said bracket and closure, whereby the latter is pressed over said opening, said rod having a lug or projection, arranged near the scraper, adapted to engage said closure to remove the same from the opening to permit of the removal of the refuse from the screen.

19. In a machine of the character described, the combination with a casing having an inlet-opening, a screen-plate arranged in said casing, and a strip arranged within the casing near the inlet-opening and extending above said opening, for the purpose specified.

In testimony whereof I affix my signature in presence of two witnesses.
